J. P. Hutchinson, Attorney

UNITED STATES PATENT OFFICE

ARTHUR KUHN, OF RECKLINGHAUSEN, GERMANY, ASSIGNOR TO THE FIRM CARL STILL, OF RECKLINGHAUSEN, GERMANY

DISTILLATION OR LIKE COLUMN

Application filed March 15, 1926, Serial No. 94,891, and in Great Britain March 24, 1925.

This invention relates broadly to means for securing together separate parts of distillation and like columns and specifically for securing the plates within the casings and the vapor distributing hoods to the plates.

Heretofore, these plates have been secured within the column casings by bolts and packings, which packings consisted of sulphur or mixtures of sulphur, asbestos talc and sodium silicate, which became brittle and cracked thus leaving spaces where leakage took place. Also where similar packings were employed without the use of bolts the brittleness made the connection between the parts very insecure and lacking in durability.

It is therefore the object of this invention to provide a simple, inexpensive and efficient connection between the several parts to be connected and specifically between the plates and the column casings and the vapor distributing hoods and the plates, which is extremely rigid and which is sufficiently tight to practically prevent leakage.

Another object of the invention is the provision of a connection between the separate parts to be connected, which is extremely rigid and yet which may be readily removed in case it becomes necessary to separate the connected parts.

Further objects of the invention will appear as the following specific description is read in connection with the accompanying drawing, which forms a part of this application and in which:

Figure 1 is a vertical sectional view taken through a portion of a distillation column constructed in accordance with this invention,

Figure 2 is a plan view, and

Fig. 3 is a detail of Fig. 1 in an enlarged scale.

Referring more particularly to the drawing, *a* represents a single ring forming a portion of a casing of a distillation column and

within said ring are located the two plates *b* having mounted thereon the bell-shaped vapor distributing hoods *c* covering the vapor inlets *d*. The plates *b* are provided, as is usual, with overflow outlets *e* which are located in alternate plates adjacent the periphery and at the center thereof. A small hole *i* in each plate *b* serves for automatically emptying the column at the end of the process. 50

In the ring or casing *a* I have shown vertically spaced inwardly extending flanges *f*, *f'* the latter of which is somewhat narrower than the former so as to permit the lower plate to pass and rest upon the flange *f*. Each flange *f*, *f'* is provided upon its upper face with a rabbet, the inner vertical wall of which being undercut as shown for a purpose which will be clearly apparent from what follows. 60

The plates *b* rest upon the lower horizontal wall of the rabbet and are provided with bevelled edges, as shown, which coact with the inner vertical wall of the rabbet and the lower horizontal wall of the rabbet to form a substantially frusto-triangular or dove tail shaped groove, wider at its base than at the upper open portion of the same. (See Fig. 3.) 65

In constructing the plates *b* and the rabbeted flanges *f*, *f'* the lower peripherical edge of the plates are just sufficiently smaller than the upper edge of the vertical wall of the rabbet to pass the same, but the angle of the bevel on the periphery of the plates is not as great as the angle of the undercut of the inner wall of the rabbet. The groove *m* thus formed is substantially frusto-triangular and is filled with some suitable calking material, such for instance, as molten lead, solid lead wire or lead wool, which may be subsequently firmly packed into the groove *m* by the use of any preferred type of calking tool. 70

In order to couple the bell-shaped vapor distributing hoods *c* to the plates, there is 80

- formed upon the upper surface of each plate, in sets of three, triangularly disposed lugs *k* having an undercut rear wall which co-acts with the bevelled outer edges of the feet *h*, formed on the hoods, to produce a groove *n* similar to the groove *m* which holds the packing for connecting the plates to the column casing. The lugs *k* are also provided with parallel extensions *k'* extending forwardly from the rear wall between which the feet *h* are disposed and which serve to prevent leakage of the molten metal, in case such is used, or undue expansion of the packing material when being calked into the groove. 5
- 15 By connecting the parts as above described, it will be seen that I have provided a very rigid and permanent connection which avoids the use of screws, bolts and similar connecting means which are liable to come loose and thus permit leaks which would be detrimental to the process. If, however, it is desirable to disconnect either the hoods from the plates or the plates from the casing the calked metal may be removed by mechanical means or 20 may be brought to a state of fluidity by the application of heat which will permit of the ready separation of the connected parts. 25
- What I claim is:
1. Means for securing together separate parts of distillation and like columns comprising a support, a vertically disposed wall rising from the support and being undercut, a member resting on the support and having the edge presented to the wall bevelled, 30 so as to coact with the undercut to produce a groove, the inclination of the undercut and the bevelled edge being in the same general direction, and calking metal filling said groove. 35
  2. In a means for securing together separate parts of distillation and like columns, the combination with a partition plate, opposed lugs rising therefrom each provided with undercut shoulders, a vapor hood arranged between said lugs and having means coacting with said shoulders to produce tapered grooves, and calking metal filling said grooves. 40
  3. In a means for securing together separate parts of distillation and like columns, the combination with a partition plate, integral lugs rising therefrom and having undercut shoulders, a vapor hood arranged between said lugs, projections on said hood 45 having inclined faces coacting with the undercut grooves to produce substantially trapezoidal grooves, and calking metal filling said grooves. 50
  4. In a means for securing together separate parts of distillation and like columns, the combination with a partition plate having a vapor collar thereon, a plurality of lugs arranged around said collar each having an undercut shoulder terminated by parallel extensions, a vapor hood arranged over the 55
- collar and between said lugs, and projections on said hood having inclined faces coacting with said shoulders to produce substantially trapezoidal grooves, and calking metal filling said grooves, said projections arranged 70 between the extensions of the lugs. 75
5. The method of securing together separate parts of distillation and like columns, which consists in providing a support having several opposed parts rising therefrom, and in forming the other part so as to coact with the support and the parts rising therefrom to produce substantially trapezoidal grooves, and filling said grooves with calking metal. 80
- In testimony whereof I affix my signature. 85
